UNITED STATES PATENT OFFICE.

EVAN SHELBY, OF WEST LAFAYETTE, INDIANA.

TELEPHONE OR TELEGRAPH SYSTEM.

SPECIFICATION forming part of Letters Patent No. 700,380, dated May 20, 1902.

Application filed September 17, 1900. Serial No. 30,294. (No model.)

To all whom it may concern:

Be it known that I, EVAN SHELBY, of West Lafayette, county of Tippecanoe, and State of Indiana, have invented a certain new and 5 useful Telephone or Telegraph System; and I do hereby declare that the following is a full, clear, and exact description thereof, reference being had to the accompanying drawings, in which like numerals refer to like parts.

10 This invention relates to a telephone or telegraph system to enable one to cut into regular telephone or telegraph lines at an intermediate point without affecting the use of the regular lines excepting when the intermediate telephone or telegraph connection is 15 in use. The intermediate telephone or telegraph connection is a permanent one mounted on the telephone or telegraph pole or any other convenient or suitable means. When 20 it is not being used, the regular lines with which it is connected will not be affected.

One of the important uses of this system is to provide telephones for police-calls or patrol-boxes, fire-alarms, or any similar purpose. 25 For illustration, this system for police-calls can be introduced by merely placing jacks inclosed in suitable boxes on the telephone-poles at various points in a town or city and connecting the boxes with the regular telephone-wires above. This avoids the necessity of an independent telephone system for such purposes and does not materially interfere with the use of the regular lines.

The full nature of this invention will be 35 understood from the accompanying drawings and the description and claims following.

In the drawings, Figure 1 is a perspective of a portion of a telephone-pole broken away at the lower end and midway and carrying 40 telephone-wires and having a box for a jack mounted thereon to show one use of this system. Fig. 2 is a central longitudinal section of the jack employed in connecting the telephone or telegraph instrument by means of 45 a plug with the regular telephone or telegraph lines above. Fig. 3 is a part of Fig. 2 with the plug in place in the jack and partly broken away. Fig. 4 is a diagram of the circuits and wiring in said system.

50 In detail, 1 represents a telephone-pole having on its upper end the cross-arm 2, carrying

ing the ordinary conducting-wires connecting the telephones of subscribers with the central office, including the wires 3 and 4, which form two sides of the circuit running to one 55 telephone from the central-station set. In the wire 3 or one of said wires which forms one side of the circuit a break is made by means of the intervening wire or connection 5, so as to separate the portions of the wire 3 60 on each side of the cross-arm 2 and insulate them from each other. From each of the adjacent ends of the main wire 3 thus separated wires 6 and 7 are extended down into the box 8 to the spring-jack at 10, and when 65 said spring-jack is not in use the parts are so arranged, as will hereinafter appear, as to maintain connection between the wires 6 and 7. In such cases the circuit from one portion of the wire 3 passes through the wires 6 70 and 7 to the other portion of the wire 3, and the line can be used the same as if it were not broken.

The box is secured to the telephone-pole 1 down low enough to be accessible to a person 75 standing on the ground and is provided with a door 9, capable of being locked, and the spring-jack, that is shown in Fig. 2. The jack is preferably located in the door and secured therein by the ring-nut 10, which screws into 80 the internally-threaded collar 12 on the outer end of the tubular-casing 13 of the jack.

The jack has two conducting-springs 15 and 16 and two conducting-strips 14 and 17, secured in place by the screws 18 and at the 85 point of mounting insulated from each other and from the screws by the insulating-strips 19, 20, 21, and 22. At their outer ends the springs 15 and 16 are bent to form contact-points that engage the plug 35 when in place. 90 For that purpose the tubular casing 13 is slotted to let the ends of said spring extend into said casing, substantially as shown in Fig. 2, when the plug is out. In the unused condition the spring 15 is out of contact with the 95 strip 14 and in contact with the strip 17. The spring 16 is out of contact with the other springs and strips at all times. The strip 17, which is stationary, as here shown, has a conducting-pin 23 extending from it into contact 100 with the spring 15 when there is no plug in the jack. When a plug is inserted, it first

pushes the spring 15 outward, whereby it contacts with contact-point 24 on the spring 14, and it ceases to engage the pin 23 on the strip 17, thus discontinuing service on the subscriber's telephone and enabling the operator to have private and undisturbed use. When the plug is pushed in fully at its inner end, it engages the inclined surface 25 on the outer end of the spring 16, thus making contact 10 with said spring and at the same time crowding said spring outward, as appears in Fig. 3. Said outward movement of the spring 16 causes it, through the insulating projection 26, secured to the strip 14, to push said strip 15 out of contact with spring 15. Then spring 14 is out of contact with any other spring or strip.

In the box 8 or somewhere else a suitable battery 27 is placed, said battery not being shown here excepting in the diagram. The wire 6 is connected with spring 17 on the jack and wire 7 with spring 15. Wire 28 connects the spring 16 with the battery 27, and wire 29 (shown in Figs. 1 and 4) extends from the battery to the return-wire of the circuit. The wire 30 connects the wire 28 with strip 14 in the jack.

The wiring and circuits of the system appear in Fig. 4. 31 represents a subscriber's telephone. Wire 3 runs therefrom through the connections just described to the central office (represented by the jack 32 at the other end of the diagram and the drop 33.) 4 is the return-wire. This diagram shows the wiring and circuits as they exist while the intermediate-telephone connection herein shown is not in use. Thus in the diagram the wire 3 from the subscriber's telephone connects with the wire 6, and the circuit runs through 35 the spring or conducting-strip 17 and through pin 23 to the spring 15 and then through the wire 7 back to the other portion of the line 3, making an unbroken line from the subscriber's telephone to the central office. In such 40 case the subscriber can use his telephone without any inconvenience or interruption by reason of the intermediate-telephone arrangement. When, however, the intermediate telephone 36 is used, the plug 35 is inserted in 45 the jack. In the first place it moves the end of the spring 15 into momentary contact with the strip 14 and out of contact with the pin 23, thus breaking connection with the subscriber's telephone and making a short circuit 50 through the battery to the central office. When the plug is fully inserted, the spring 15 is still held away from the pin 23 and the circuit is complete through the telephone. During the use of this intermediate telephone 55 it is therefore apparent that the regular subscriber's telephone is cut out. When the intermediate-telephone plug is withdrawn, the parts resume the position indicated by diagram in Fig. 4, and then the subscriber can 60 use his telephone, as before. In ordinary use the door of the box 8 does not have to be opened. No one excepting the electrical re-

pair man need enter the box or have a key for it. The policeman or other individual needs only to insert the plug of the telephone 70 instrument in the jack, as has been explained, do his telephoning, and withdraw the plug. For this use a pocket-telephone is best.

While the above description, as well as the drawings, show a telephone system, the same 75 construction, arrangement, and principle are equally well adapted to a telegraph system, there being no difference in the wiring or the jack.

What I claim as my invention, and desire 80 to secure by Letters Patent, is—

1. In a telephone and telegraph system, a spring-jack including a pair of contact-strips normally in contact, and a pair of contact-strips normally isolated but capable of alternative connection with one strip of the first pair after it is separated from the other strip 85 of the first pair.

2. In a telephone and telegraph system, a spring-jack including a pair of contact-strips 90 normally in contact, a pair of contact-strips normally isolated, and a plug that separates the first pair of contact-strips and while entering connects one of the first pair with one of the second pair and when in place leaves 95 the latter separated but connects one strip of the first pair with the other strip of the second pair.

3. In a telephone or telegraph system, a jack having two springs engaged by the plug when 100 inserted, and two conducting-strips not engaged by the plug, one of said springs being connected with one of the strips while the jack is not in use and disconnected while in use, and momentarily connected with the 105 other strip while the plug is being inserted in the jack.

4. In a telephone or telegraph system, a jack having two springs engaged by the plug when 110 inserted and two conducting-strips not engaged by the plug, one of said springs being connected with one of said strips when the jack is not in use, and adapted to be held away from said strip by the plug when inserted and momentarily connected with the other strip 115 as the plug is being inserted, and insulating means whereby said strip is disconnected by the other spring when it is engaged by the plug.

5. In a telephone and telegraph system, the 120 two wires of a circuit, one of which wires is broken or separated, a spring-jack having a pair of contact-strips normally in contact with each other and connected with the respective ends of the broken wire and a pair of contact-strips normally isolated but capable of alternative connection with one strip of the first pair after it is separated from the other strip of the first pair, and a connection between said second pair of strips and the unbroken wire 130 of the circuit.

6. A telephone or telegraph system including the two wires of a circuit, one of which wires is broken, a jack, having two springs

adapted to be engaged by the plug, when inserted and two conducting strips not engaged by the plug, one of said springs being connected with one of the strips while the jack 5 is not in use and disconnected while in use and momentarily connected with the other strip while the plug is being inserted in the jack, wires leading from said connecting spring and strip to the members of the broken 10 circuit-wire, a battery, wires leading from the

other spring and strip to the battery, and a wire from the battery to the unbroken circuit-wire.

In witness whereof I have hereunto affixed my signature in the presence of the witnesses 15 herein named.

EVAN SHELBY.
